**PHOTOTYPOGRAPHIC STRIP PRINTING
MACHINE**

Bruno Radtke, Libertyville, Ill., assignor to Fototype, Incorporated, Chicago, Ill., a corporation of Delaware
Filed Nov. 5, 1964, Ser. No. 409,113
13 Claims. (Cl. 95—4.5)

This invention relates to a strip printing mechanism, and more particularly to such a mechanism for producing display lines of type of various character and size for use by lithographers, etc.

Various type of devices and mechanisms have heretofore been provided for producing photolithographs with different sizes and styles of type, etc. Such mechanisms or devices as heretofore used have been subject to one or more drawbacks, including slow operation, expendable materials which cannot be reused, requirements of too much skill on the part of the operator, undue initial expense, limited versatility, etc.

The general object of the present invention is to provide a new and improved photographic compositor.

It is also an object of this invention to provide a new and improved strip printing machine or mechanism.

It is further an object of this invention to provide a photographic compositor or strip printing machine wherein the spacing between individual letters or characters is adjustable, but wherein once the adjustment is made a constant spacing is maintained irrespective of the width of each individual letter or character.

More specifically, it is an object of this invention to provide a strip printing mechanism or photographic compositor wherein the type font is used to control spacing between letters, whereby uniform spacing is maintained regardless of the width of each letter, and whereby proper spacing is obtained irrespective of degree of magnification or minification relative to the original type font.

It is yet another object of this invention to provide a strip printing mechanism or photographic compositor wherein, once a set up has been made, the operator need only rotate a selector for reproducing individual letters or characters and to push a button or control to produce a complete printing operation, irrespective of development of the photosensitive paper.

It is still a further object of the present invention to provide a strip printing mechanism or photographic compositor wherein standard components are used for the optical portion of the mechanism.

It is yet another object of this invention to provide a photographic compositor or strip printing mechanism which is of sufficient mass to prevent unwanted migration in use, yet which is separable into several parts for ready transportation.

One specific object of this invention is to provide a strip printing mechanism or photographic compositor utilizing an electric eye to produce precise predetermined spacing between successive letters or characters.

Another specific example of this invention is to provide means for precisely advancing a strip of photosensitive paper a predetermined but variable degree as a part of a letter or character printing cycle, the degree of advancement being dependent on the size of the letter or character.

Various additional objects and advantages of the present invention will be apparent from the following description when taken in connection with the accompanying drawings wherein:

FIG. 1 is a front elevational view;

FIG. 2 is a plan view;

FIG. 3 is a sectional view taken along the line 3—3 of FIG. 1;

2

FIG. 3a is a fragmentary sectional view of a modification of a portion of FIG. 3;

FIG. 4 is a sectional view similar to FIG. 3 taken along the line 3—3 of FIG. 1 showing a shifted position of the lenses;

FIG. 5 is a diagrammatic view of cooperating parts such as the light source, lenses, photocell, etc.;

FIGS. 6, 6a, 6b are views of slides to illustrate different letters in the alphabet;

FIG. 7 is an enlarged sectional view taken along the line 7—7 of FIG. 1;

FIG. 8 is a perspective view of the paper strip guide;

FIG. 9 is an enlarged sectional view taken along the line 9—9 in FIG. 1;

FIG. 10 is a perspective view of the mounting for the photo electric cell;

FIG. 11 is a perspective view of the bracket and scale supported thereby;

FIG. 12 is a sectional view taken along the line 12—12 of FIG. 9;

FIG. 13 is a fragmentary sectional view of the indicator mechanism taken along the line 3—3 of FIG. 7;

FIG. 14 is a perspective view of the shutter mechanism;

FIG. 15 is a plan sectional view taken along the line 15—15 of FIG. 12;

FIG. 16 is a plan sectional view taken along the line 16—16 of FIG. 12;

FIG. 17 is a fragmentary detailed sectional view of the paper driving and control mechanism taken along the line 17—17 of FIG. 9;

FIG. 18 is a view similar to FIG. 17 showing a disengaged position of the drive roller;

FIG. 19 discloses a fragmentary portion of a strip of photographic paper after it has passed through the machine and has been developed to show the lettering thereon, together with a diagrammatic representation of rectangles simulating the rectangles on the slides which automatically control the extent of intermittent travel of the photographic paper strip;

FIG. 20 is a wiring diagram.

Referring now in greater particularity to the drawings, and first to FIGS. 1—4, a strip printer or photocompositor constructed in accordance with the present invention is identified generally by the numeral 30. The apparatus, device or mechanism (the strip printer) 30 comprises four major parts, a base 32, a photographic projection portion, unit, or assembly 34, a printing portion, unit or assembly 36, and an electric control unit 38.

The base 32 comprises a steel channel somewhat under three feet in length, and having a web 40 and a pair of depending flanges 42 adapted to rest on a table or other suitable supporting surface. An elongated guide member 44 extends from near the left end (as viewed in the drawings, and particularly FIGS. 1 and 2) of the web 40 to a point somewhat to the right of the center thereof. This guide member 44 is disposed relatively toward the side of the web adjacent the operator and is generally semi-cylindrical in shape. Immediately to the side of the guide member 44 and disposed opposite the operator, there is provided a rack 46, also fixed to the top of the web.

The projection unit 34 comprises a box-like housing 48 with a removable cover or lid 50. The housing is provided internally thereof on the side opposite from the operator with a roller 52 resting on the web 40 of the base 32. Portions of the housing interfit with the guide 44 as at 54, and near the left forward corner of the housing there is provided internally thereof a gear 56 meshing with the rack 46, and fixed on a shaft 58 rotatable by a

knob 60 disposed exteriorly of the housing for moving the projection unit 34 to the right or to the left.

The housing is provided with a photographic slide changing apparatus including a rotary slide tray 62 disposed in substantially a vertical plane and rotatable about a horizontal axis, and further including a finger piece or handle 64 for moving a selected slide to and from the slide tray or carrier 62 and a projecting station. The specific details of the slide changer mechanism are not shown herein, since this is a device widely available in commerce. One suitable circular slide tray and changing mechanism is that which is incorporated in the "Romatic" slide projectors made by Sawyer's Inc. of Portland, Oreg.

The optical system also may be conventional in nature, and hence is shown only schematically in FIG. 5, including a projection bulb 65, a mirror 66 therebehind, condensing lenses 68, and a projection gate 70. A projecting lens 72 is mounted within a tubular member 74 which is in focusing mount to be described hereinafter, and which also incorporates an iris diaphragm 76 for regulating the amount of light passing through the projection lens 72 in accordance with conventional photographic principles.

The actual structure of the projection lens and accompanying parts will be seen with particular reference to FIGS. 1-4. As is seen in these figures, a vertical plate 78 is movably mounted from the housing 48 by means of a pair of lower guide rods 80 and 82 slidable in suitable guides in the housing 48, and further by means of an upper tube 84. The upper tube is concentric with the tube 74 holding the projection lens 72, and it will be seen in FIGS. 1 and 2 that this tube is provided with a knurled section 86 for adjusting the iris diaphragm 76. Bolts or cap screws 88 pass through the plate 78 and are threaded into tapped holes in the ends of the rods 80 and 82 to secure the plate to the rods, and suitable hardware 90 is provided to hold the plate to the upper tube 84.

The rod 80 interiorly of the housing 48 is provided with an undersection in the form of a rack 92. A gear 94 meshes with this rack, and is fast on a shaft with an exterior, knurled knob 96. Upon turning of the knob 96 one way or another, the structure mounting the projection lens is moved to the right or to the left, whereby to focus the image projected by the lens.

Auxiliary lenses 98 and 100 are mounted on a plate 102 fixed on a rod 104 projecting forwardly from the plate 78 and rotatable relative thereto. One or the other of these lenses may be moved into position in front of the normal projection lens 72 to provide for focusing beyond the range of the normal projection lens. To effect such positioning, a cam 106 is fixed to the rod or shaft 104 immediately forwardly of the plate 78. This cam is provided with an idle or rest position notch 108, and with a pair of lens positioning notches 110 and 112.

A pawl 114 having a sharp edge protuberance 116 projecting therefrom is pivoted about a pin or shaft 118 extending forwardly from the plate 78. A spring 120 is stretched between the tail 122 of the pawl and a pin 124 extending forwardly from the plate 78. The spring normally holds the projection 116 in one or another of the cam notches 108, 110, 112. With the projection in the notch 108, as in FIG. 3, the auxiliary lenses 98 and 100 are positioned out of the optical path of the lens 72. When the projection is in the notch 110, the auxiliary lens 98 is in the optical path, and when the projection is in the notch 112 (as in FIG. 4) the auxiliary lens 100 is in the optical path.

Specimen slides, which comprise the type font, are shown in FIGS. 6, 6a and 6b. As will be appreciated, the type font is changed readily by changing the slide tray or carrier, a different set of slides being stored in each tray or carrier. The slides may be in any type of slide binders 126, and preferably are of the glass bound type. Reference first should be had to FIG. 6, wherein the character

H is displayed. The H128 is transparent, while the background 130 is opaque, normally black with common photographic products, with the exception of a transparent bar 132. It will be observed that the spacing vertically in FIG. 6 between the bottom of the H, which is lying on its side, and the top of the bar 132 is rather slight.

Reference should now be had to FIG. 6a, and it will be seen that the character 128 in this instance comprises a W lying on its side. Since the width of a W is substantially greater than that of an H, it is immediately apparent that the height of the character lying on its side is considerably greater in FIG. 6a than it is in FIG. 6.

The transparent bar 132 is substantially lower on the slide in FIG. 6a than it is in 6, but it will be seen that the vertical spacing between the bottom of the sideways character W and the top of the light bar is the same slight spacing as in FIG. 6.

Turning now to FIG. 6b, it will be seen that the character 128 is narrow as possible, namely an I, again lying on its side. It is immediately apparent that the vertical height of this sideways I is less than that of the H, and much less than that of the W. Nevertheless, the spacing from the bottom of this character to the top of the light bar 132 is again the same slight spacing as in FIG. 6 and FIG. 6a. The significance of this is that the top of the light bar 132 is used to control the spacing of the characters or letters as printed in the printer 36, and the details of this will be brought out hereinafter.

Reference to FIG. 1 reveals a scale 134 with indicia therein readable against the right end of the housing 48. The scale is movable with the plate 78, and is used for focusing without the necessity of observing the projected image. Similarly, a scale 136 is provided on the base 42 and has indicia thereon readable against an index mark 138 on the side of the housing. This scale provides for producing a predetermined size of image, also without the necessity of observing the projected image.

The printer or printing assembly 36 is horizontally and vertically adjustable, and reference should be had to FIGS. 7, 9 and 12, as well as to FIGS. 1 and 2, for a more complete understanding of the printing assembly. The top web 40 of the base 32 has an opening 144 of substantial size therein near the right end of the machine, as best seen in FIG. 2. Part of the printing assembly depends into this opening, as will be apparent immediately hereinafter.

A mounting block 146 is spaced up from the web 142 by spacer blocks 148 at the right end of the opening 144, and cap screws or machine bolts 150 extend down through the block 146 and the spacers 148, and are threaded into the web 142, although it is contemplated that nuts could be provided beneath the web on these cap screws or machine bolts. A vertical adjustment spacer block 152 of generally L-shape has a horizontal portion or leg 154 thereof extending beneath the central portion of the plate 146 in an extension slot 156 forming a part of the opening 144. A cap screw or machine bolt 158 extends through the plate 146 and is threaded into a tapped hole in the block portion 154. Dowel pins 160 also extend through the plate 146 into suitable apertures in the block horizontal portion 154 to aid in securing the block to the plate 146. The block 152 also includes a vertically upstanding portion 162 having a central threaded bore 164 for receipt of a vertical adjustment screw 166 having a knurled head 168 readily grasped by the fingers. The head is provided on its underside with a boss 170 riding against the top of a reaction plate 172, while a washer or flange 174 on the screw 166 rides against the underside of the reaction plate 172.

A generally rectangular plate 176 extends from front to back of the printing mechanism. Spacer blocks 178 and 180 lie vertically along opposite sides thereof, and a plate 182 is held across the top right end thereof by

bolts 184 which extend through the plate 182 and through the spacer blocks 178 and 180, and are threaded into the plate 176. Pins 185 also extend through the plate 182 and into the spacer blocks 178 and 180 for aid in mounting the parts together. A holding or stabilizing plate 186 overlies one side portion of the generally L-shaped block 152 to the backside of the horizontal projection 154. This plate is held in place by a pair of bolts 188 extending through the plate 186 and threaded into the block 180.

As will now be seen, the block 156 is fixedly mounted. Hence, turning of the thumb wheel 168 to advance or retract the screw 166 in the vertical portion 162 of the block 152 causes the horizontal plate 172 to be raised or lowered. This plate is secured to the vertical plate 176 by a means including a bolt 190 extending vertically down through the plate 172 and threaded into the plate 176. Hence, the plate 176 and the parts attached thereto, including the main part of the printing device are raised or lowered by such turning.

As will be seen with reference to FIG. 1, a vertical scale 192 is provided on the forward portion of the spacer block 178, and this also may be seen to some extent in FIG. 9, although the indicia on the scale 192 are not visible in FIG. 9. A pointer 194 extends from the top of the plate 146 for reading against the indicia 192, thereby to determine the proper height of the printing device or assembly.

A guide plate 196, seen in FIGS. 7 and 12, is secured to the left side of the plate 176 by means of bolts 198 countersunk in the guide plate 196 and extending through a spacer block 200 and threaded into the plate 176. The plate 172 partially overlies the space between the plate 176 and the guide plate 196, as will be seen in FIG. 12, and a slide block 202 is mounted therein, having an upstanding vertical plate 204 of rather substantial height secured thereto as by recessed screws 206.

The block 202 is provided with a threaded bore 208, and the threaded shank 210 of a horizontal adjustment screw 212 is threadedly received therein. The adjustment screw 212 is provided at its outer end with a knurled hand wheel 214 (see also FIG. 9) having an underlying boss 216. This boss bears against a reaction plate 218 which is secured to the guide plate 196 by means of screws or bolts 220 extending through the plate and threaded into tapped apertures in the guide plate 196. A collar 222 is fixed on the shank 210 of the horizontal adjustment screw and abuts the inner face of the plate 218. Thus, rotation of the hand wheel 214 causes the block 202 to move in or out, and thereby to shift the upper portion of the printing assembly forward or backwards relative to the base.

Near the top of the plate 204 and on the far side thereof, there is secured a channel shaped support 224, (FIGS. 2, 7, 9, 15 and 16) having a relatively wide flange 226 secured to the plate 204 by screws (not shown). The support 224 also includes a web 228, and a smaller flange 230. The web depends below the lower edges of the flanges 226 and 230, and is deflected outwardly at 232.

A drive unit 234 is secured to the web 228 by means of screws and spacers 236, and is of known construction, including a reducing gear unit 238 and an electric motor 240. The motor is of a type in which the rotor is free to turn relative to the shaft, and which is clutched thereto through a solenoid 242 when the solenoid is energized for operation. The entire drive unit 234 may be seen somewhat generally in FIG. 2, wherein the clutch is indicated at 244 between the motor 240 and the drive shaft 246.

The output shaft 245 from the gear reducer 238 extends through the web 228 and has a drive gear 248 (FIGS. 7 and 12) fixed on the end thereof. This drive gear meshes with an overlying driven gear 250 (FIGS. 2, 7, 12 and 15) fixed on a shaft 252 journaled in bearings in vertical plates 254 and 256 extending to the left

from the plate 204 and suitably secured thereto, preferably by screws passing through the plate 204 and threaded into the plate 254 and 256, such screws not appearing in the drawings.

- 5 Between the plates 254 and 256 a rubber roller 258 is fixed to the shaft 252 for rotation therewith. In addition, a gear 260 is fixed on the shaft and meshes with a like gear 262 fixed on a shaft 264 and carrying a rubber roller 266 in opposition to the rubber roller 258.
- 10 It will be apparent that the two gears and the two rubber rollers are thus driven in synchronism.

The shaft 264 is journaled in bearings in slide blocks 268 fitting in recesses in the plates 254 and 256. The recesses are closed over by small plates 270 and held in place by screws, and helical springs 272 recessed within the bearing blocks 268 react against the plates in order resiliently to hold the rubber roller 266 against the roller 258.

- 15 A vertical depending flange 274 (FIG. 12) of a paper storage container support 276 is secured to the top edge of the plate 204 by means such as screws 278. The support 276 also includes a horizontal plate portion 279, an upstanding web 280, and a reentrant floor 282 depending at the left edge as a vertical flange 284.

20 25 A paper storage box 286 is suitably secured to the support 276 and carries a roll 288 of photosensitive paper which unrolls therefrom as a strip 290. The box 286 is light, tight, and includes a flanged cover 292 (FIGS. 7 and 9) held in place by a stud 294 extending from the back wall 296 through the cover 292. The outer or forward end of the stud 294 is threaded, and a knurled nut 298 is turned down thereon to hold the cover removably in place.

- 30 35 A paper guide 300, comprising a pair of spaced apart plates, one of which has an outwardly turned flange 301 for facilitating paper strip entrance, depends from the paper storage box 286 and has side flanges thereon (not shown) to exclude light. The guide extends almost to the entrance or maw of the rollers 258 and 266 to guide the paper strip 290 to a position for feeding between the rollers.

40 45 Spaced slightly below the rollers, there is a backup plate 302 having an outwardly turned upper edge 304 properly to receive the paper strip. The upper portion of this backup plate comprises a printing area, and below this printing area there is a forward guide plate 306 also having an outwardly turned upper flange 308 to facilitate paper strip guidance. Screws 310 extend through the plates 306 and 302, and also through shims 312 (FIG. 50 16) between them and through spacer sleeves 314, the screws being threaded into the plate 204 in suitably tapped apertures. The plates 306 and 302 preferably are otherwise secured to themselves and to the shims 312, as by spot welding.

- 55 50 A plate 316 (FIGS. 7 and 12) is secured across the undersides of the bearing blocks 254 and 256, by means such as suitable screws (not shown), and has a fixed cutting blade 318 secured to the underside thereof. A movable cutting blade 320 is pivotally fixed to the underside of the fixed cutting blade as by a pivot screw 322. As will be appreciated, this is immediately above the out-turned flange 304 on the backup plate 302, and provision thus is made for cutting off the paper immediately below the rollers and just above the backup plate 302.

60 65 A shaft 324 (FIGS. 7, 15, 16 and especially 14) is pivotally mounted between the flanges 226 and 230 of the support 224. A shutter plate 326 has a boss 328 thereon fixed to the shaft 324 by suitable means, such as a set screw 330. The boss engages the inner end of a bearing 332 set into the plate 230, there being a like bearing set in the plate 226. A pin 334 extends to the left from the shutter plate 326, and a helical spring 336 is stretched between this pin and a fixed pin 338 on the inner side of the flange 230. The spring 336 thus holds the shutter plate 326 to its normal raised position. The pin also is en-

gageable with the front edge of the flange 230 to serve as a limit stop for the downwardly pivoted position of the shutter plate 326.

The shutter plate 326 has a shutter blade 338 secured thereto, as by rivets 340. The shutter blade is generally rectangular and is provided along its upper edge with a right angled, V-shaped notch 342. In its normal, raised position of operation as shown in solid lines in the drawings, the shutter blade overlies the printing area at the top of the plate 302, as perhaps best can be seen in FIG. 12. In the lowered, printing position of FIG. 7 shown in dashed lines, the shutter blade is at approximately a 45° angle, and the notch 342 has its sides respectively lying vertical and horizontal, thereby to expose a rectangular printing area without requiring a more extensive pivot angle of the shutter.

At the opposite end of the shaft 324, there is provided a lever arm 344 which also extends in a horizontal direction in rest position. This arm, as best seen in FIGS. 9 and 14 (and also in FIGS. 15 and 16), has a connecting link 346 pivoted thereto, and also pivotally connected to the upper end of the plunger 348 of a solenoid 350 mounted on the previously noted outturned bottom flange 232 forming the extension of the web 228 of the support 224. As will be appreciated, energization of this solenoid pulls down on the arm 344, and thus pivots the shutter blade 338 to printing position, as determined by engagement of the pin 334 against the front of the flange 230.

The extreme right end of the shaft 324 also is provided with an operating cam 352 having a boss or spacer 356 secured thereto and to the shaft 324. This cam is provided with a tapered leading edge 358, and its function will be described more fully hereinafter.

Means is provided to determine how far the strip of paper 290 will be advanced by the rollers 258 and 266 in any given operation, and the structure thereof is set forth immediately hereinafter.

A forward bearing block 360 (see particularly FIGS. 9, 15, 16) and a rear bearing block 362 (see also FIGS. 12, 17 and 18) are secured to the right face of the plate 204 in parallel spaced apart relation by means such as screws 364. A shaft 366 is journaled between these plates, and has fixed thereto a clevis 368 having a bight 370 secured to the shaft as by set screws (not shown), and a forward arm 372 integral therewith, and a rear arm 374 also integral therewith, the arms being respectively adjacent the forward and rear bearing blocks or plates 360.

The clevis arms 372 and 374 at their upper ends carry a rotatable shaft 376 extending between them and also forwardly of the forward clevis arm 372. A rubber roller 378 is fixed to this shaft, and projects through an opening 380 in the plate 204 into driven engagement with the roller 258.

The shaft 366 has a depending arm 382 (FIGS. 17 and 18) fixed thereon, and a spring 384 is stretched between this arm and a screw 386 in the underside of the block 362 so as resiliently to bias the roller 378 into engagement with the roller 258, as shown in FIG. 17.

The arm 382 also is provided with a pin 388 rotatably carrying a metal roller 390. An opposed metal roller 392 rotates about a pin 394 fixed on the block 362. The two rollers 390 and 392 normally are spaced apart a rather small distance as shown in FIG. 17. They are positioned so that when the shaft 324 is rocked by operation of the solenoid 350, the cam 352 is pivoted into place between these two rollers to cam the rollers apart, as shown in FIG. 18, thereby withdrawing the rubber roller 378 from engagement with the roller 258. As will be apparent in FIG. 18, the tapered leading edge 358 of the cam 352 facilitates entrance into the space between the two rollers 390 and 392.

The shaft 376 at its forward end has a gear 396 (FIGS. 9, 13 and 15) fixed thereto. The gear has a boss 398 fixed for turning therewith, and a pointer 400 extends radially

therefrom. The pointer reads against indicia on a segmental scale 402 supported by means of screws 404 passing through a right angle flange 406 thereon and threaded into a block 408 screwed or otherwise suitably fixed to the forward clevis arm 372. The forward end of the block 408 is bifurcated and a threaded shaft 410 (see also FIG. 11) is threaded therethrough and is provided with a knurled knob 412. The opposite ends of the threaded shaft 410 is engageable with an arm 414 fixed on the shaft 398 to determine a limit position of the pointer 400, and hence also of the gear 396.

The gear 396 meshes with a gear 416 which is freely rotatable on the shaft 366. A smaller gear 418 is formed integral with the gear 416, and meshes with the teeth of a gear segment 420 fixed on a shaft 422 journaled in the plates or blocks 360 and 362. A boss 424 serves to space the segment 420 forwardly of the block 360.

On the backside of the block 360, there is a boss 426 fixed to the shaft and having fixed thereto an arm 428. A helical spring 430 is stretched between this arm and a hole in the horizontal wall 278 of the storage box base.

Substantially diametrically opposite to the arm 428 there is an arm 432 extending beneath the operating button 434 of a low travel switch 436 mounted in a bracket 438 on top of the bearing block 362. As may be seen in FIGS. 9, 15 and 16, the arm 432 is spaced from the arm 428 and has a boss or collar 440 to which it is secured, and which is in turn fixed to the shaft 422.

A long arm 442 (FIGS. 10, 13, 15 and 16) extends to the left from the shaft 422, to which it is fixed immediately adjacent the boss 424, as by being fixed to this boss. This arm is provided with an arcuate cutout 444 for clearing a boss 445 serving to space the gears 416 and 418 from the adjacent block 360. The arm 442 is provided with an integral, lateral arm 446 having upper and lower flanges 448 thereon.

A slide 450 is mounted against the arm 446 between the flanges 448, and is adjustable longitudinally thereof. The slide is provided with a central, longitudinal aperture 452, and a threaded stud having a knurled head 454 extends therethrough and is received in a nut 456 welded or otherwise suitably secured to the back of the arm 446.

The slide is provided along its upper edge with a scale 458 readable against the end (the right end in FIG. 10) of the upper flange 448. At the opposite end, the slide 450 carries a photocell assembly 460, mounted to the slide 450 by means such as screws 462. The photocell assembly is provided with a very small window 464 (small in a horizontal direction) providing light access to the photocell therebehind.

The photocell assembly is normally positioned slightly forward (to the right in FIGS. 7 and 8) of the shutter and printing area, and is movable into position closely adjacent to the strip, and immediately adjacent the recessed portion 466 (FIG. 8) of the plate 302. This is used when letters are being printed quite small. Contrarywise, the photocell assembly is shifted far to the right of the position shown in FIG. 7 for printing letters of rather large size.

An electric terminal block 468 is shown mounted on the flange 226 in FIG. 9. The terminal block is of conventional nature, and the wires connected thereto are not shown in FIG. 9, due to the confusion that would result therefrom.

A low travel switch 470 is mounted on the flange 226 below the terminal board 268, and the operating button or plunger 472 thereof is positioned for engagement by the arm 344 when the latter is in its uppermost position.

The electric control unit 38, as seen in FIG. 2, comprises a housing 474 connected to the printing assembly by means of a cable 476, part of which goes to the solenoid 242, and part of which goes to the terminal board 458. A conventional drop cord 478 is provided for plugging into the usual wall outlet or the like. As will be apparent, the electric control unit can be positioned substantially

tially anywhere that is desired relative to the remainder of the machine.

The electric control unit includes a standard timer 480 having a knob or pointer 482 for adjustably determining the desired time period. The control unit further includes a left push button 484, a right push button 486, a left toggle switch 488, and a right toggle switch 490.

Reference should now be had to FIG. 20 for an understanding of the control unit and the allied or connected electric parts, all shown in normal schematic fashion. Starting at the lower left hand corner of FIG. 20, the A.C. supply line, indicated by the numeral 478 applied to the drop cord, has one side connected to a fixed contact 492 of the right toggle switch 490, which comprises a single-pole, single-throw switch. The other side of this switch is connected to a line 494 which leads to a fixed contact 496 of the left push button switch 484. The switch will be seen to be a double-pole, double-throw switch with a second fixed contact 498 normally open relative to the fixed contact 496, but electrically connectable thereto by the switch shorting bar or movable contact 500. A second switch shorting bar or movable contact 502 is physically connected to the shorting bar 500, but is electrically insulated therefrom, and normally connects fixed contacts 504 and 506, these two being electrically disconnected upon depression of the push button switch 484. As will be understood, the push button is spring urged out to hold the movable contacts or shorting bars in a position shown in FIG. 20.

The fixed contact 498 is connected to a junction 508 through wire 510. This junction is connected to a relay coil 512, the other side of which is connected by a wire 514 to the opposite or left side of the supply line 478. The relay coil 512, when energized, is operative to pull movable contact 516 into closed engagement with fixed contact 518, and also to pull movable contact 520 from engagement with fixed contact 522 into engagement with fixed contact 524.

Fixed contact 518 is connected by a wire 526 to normally closed contacts comprising movable contact 528 and fixed contact 530. Fixed contact 530 is connected by a wire 532 back to the junction 508 at the top of relay coil 512.

Movable contact 516 is connected to a junction 534. This junction is connected to the wire 494, and it also is connected to movable contact 520.

Fixed contact 524 is connected to a fixed contact 536 of the right push button switch 486. A fixed contact 538 normally is electrically connected to fixed contact 536 by a shorting bar or movable contact 540. The fixed contact 538 is connected to a junction 542.

The push button switch 486 also includes fixed contacts 544 and 546 which normally are not connected together, but which are electrically connectable by a movable contact or shorting bar 548. As will be appreciated, the shorting bars 540 and 548 are physically connected, but electrically insulated for movement from the position shown to a depressed position in which the top contacts 546 and 544 are connected, and the lower contacts 536 and 538 are not connected.

The fixed contact 546 is connected to a junction 550 which is also connected to fixed contact 522. Junction 550 is connected by a wire 552 to a fixed contact 654 of left toggle switch 488. Fixed contact 554 of switch 488 is connectable by a shorting bar or movable contact 556 with fixed contact 558. Fixed contact 558 is connected by a wire 560 to a junction 562.

Movable contact 556 also is connected to a junction 564 leading to the projector lamp 64, the opposite side of the projector lamp being connected by a wire 566 to the left side of the input line 478.

Switch 488 also includes a fixed contact 568 which is not connected. There is also a fixed contact 570 connectable by the movable contact 556 to the junction 564, and fixed contact 570 is connected by a wire 572 to a junction 574.

Junction 542 is connected by a wire 576 to the electrical operating coil 578 of the timer 480, the opposite side thereof being connected by a wire 580 to the left side of the line 478.

The junction 452 also is connected to a wire 582 on which is the junction 574, and also a junction 584. The junction 584 is connected to a movable contact 586 which is normally spaced from fixed contact 588, fixed contact 588 leading to junction 562. Movable contact 586 is operated by the timer including coil 578 in known fashion.

Junction 562 is connected to the shutter solenoid 350, the opposite side of this solenoid being connected by a wire 590 to the left side of the line 478.

Fixed contact 544 of switch 486 is connected to a wire 592 having a junction 594 thereon. This junction leads through a wire 596 to the photocell 460. The opposite side of the photocell is connected by a wire 598 to a relay coil 600, the opposite side of this relay coil being connected by a wire 602 to the left side of the input line 478. The relay coil 600 is operable when energized to move the movable contact 528 out of engagement with the fixed contact 530.

Wire 582 is connected to switch 470, the switch being controlled by movement of the shutter. The opposite side of this switch goes through limit switch 436 to the motor 240, the opposite side of the motor being connected by a wire 604 to the left side of the supply line. Immediately thereabove, the left side of the supply line is connected to the clutch solenoid 242, which is returned through a line 606 to the fixed contact 504 of switch 484.

Junction 594 is connected by a wire 608 to a junction 610 between shutter switch 470 and limit switch 436, and this junction is connected by a wire 612 to fixed switch contact 506.

Operation

The first step necessary for operation is to place photo-sensitive paper in the housing 236. This is easily done by loosening the thumb nut 298 to remove the cover 232. The photosensitive paper is loaded emulsion side out and is fed manually down between the guide plates 300 into position between the rolls 258 and 266. The paper is of a type that can be handled under rather dim room lights, and does not require a dark room. As will be understood, this type of paper is well known for commercial photographic reproductions, and is readily developed in a combined chemical developer and fixture, commonly called a monobath, conveniently in a tray of the type having motor driven rollers therein to advance the paper therethrough.

The timer 480 is preconditioned by the knob 482 for a known proper time of exposure to produce a properly exposed print. The right toggle 490 is moved to the right to turn the electrical circuits on. The left toggle is then moved to the right. This closes the movable contact or shorting bar 556 against the fixed contact 554 and 558. Thus, a circuit is established from the right side of the supply line 478 through switch 490, wire 494, switch contacts 520 and 522, and wire 552 to fixed contact 554. A branch circuit then runs through the projection lamp 64 and the wire 566 to the left side of the supply line 578, thus turning on the projection lamp. Another branch circuit runs through contact 558, wire 568, and shutter solenoid 350 and back through wire 590 to the left side of the supply line 478. Thus, the shutter is retracted and the projection light is on. The handle 64 is pushed in to move a slide into projection position either before or after the light is turned on, and the slide will be projected on the plate 302 in the projection area. The hand wheel 60 then is turned one way or the other to move the projection station or assembly 34 to the right or to the left to adjust the size of the projected image. Then the wheel 96 is turned to the right or to the left to focus the image, and it may be necessary

to move one or the other of the supplementary lenses 98 and 100 into position for this. The left toggle switch 488 then is moved to the left.

It is to be understood that the foregoing is used primarily for unusual set ups, or for first getting acquainted with the machine. In normal, routine use a table or slide rule is used whereby, for a known desired size of image, the projection unit is positioned according to the mark 138 against the scale 136, and focusing is simultaneously determined by reading the scale 134 against the front edge of the housing 43. Through the normal range of operation the intensity of the projected light need not be varied. Since pure black images are being produced, there is a wide range of light intensity on the paper that is satisfactory. Under some circumstances, it may be necessary to vary the intensity of the light impinging upon the printing paper, and when this is true the knurled ring 86 may be changed to adjust the diaphragm in the projection lens. However, normally this is preset and then left alone.

With the left toggle switch to the left, the shutter is in its normal horizontal position and the projection light is off. The right push button 484 then is depressed to run the motor to advance paper into printing position. A circuit is completed from the right side of the supply line 478 through the switch 490, wire 494, switch contacts 520, 522, switch contacts 546, and 544 taken with the shorting bar 548, wire 592 to junction 594, wire 608 to junction 610, through limit switch 436 and motor 240 and back through wire 604 to the left side of the supply line, whereby to run the motor. Also from junction 610, there is a connection through the wire 612 to switch contact 506, through shorting bar 502 to switch contact 504, and through wire 606 to the clutch solenoid 242 and to the left side of the supply line. Thus, the motor runs and the clutch is engaged, whereby the rollers 258 and 266 are driven to advance the paper down to printing position. The precise distance of advance being determined by releasing the depressed push button. When the push button is released, the feed motor is deenergized, but continues to coast. However, the clutch solenoid 242 upon deenergization is spring pressed from clutch position to a position to brake the drive shaft, and hence to stop the paper substantially instantaneously.

In order to print a character or a series thereof, the slide tray 62 is rotated to desired position with the handle 64 withdrawn, and the handle 64 is pushed in to move the desired slide to projection position. The left push button 484 then is depressed. This completes a circuit from the right side of the line 478 through switch 490, switch contacts 496 and 498 with shorting bar 500 to relay 512 and back to the left side of the line 478.

Energization of the relay 512 causes the contacts 516 and 518 to close, and causes the movable contact 520 to move away from the contact 522 into engagement with the contact 524. With the contacts 516 and 518 closed, a circuit is completed from the right side of the line 478 through the switch 490 and wire 494, through the contacts 516 and 518, through wire 526 and contacts 528 and 530, and then through wire 532 back to relay 512, returning through wire 514 to the left side of line 478. Thus, the contacts 516 and 518 comprise holding contacts, and the relay 512 remains energized.

With the contact 520 closed against the contact 524, a circuit continues from the wire 494 through junction 534, the closed relay contacts 520 and 524, contacts 536 and 538 through the shorting bar 540 to junction 542. From junction 542 a circuit extends through wire 576 and timer 578 to wire 580, thus to the left side of the supply line. The timer is immediately moved away from the zero mark, and starts to run back toward it. Energization of the coil 578 of the timer closes the normally open contacts 586 and 588. The circuit is completed from the aforementioned junction 542 through wire 582, contacts 586 and 588 to shutter relay 350 and back through wire

590 to the left side of the line. Operation of the shutter relay moves the shutter to exposure making position and opens the contacts 470, whereby no power is available to the motor 240.

5 Also from the junction 542 and through the wire 582 there is a circuit leading to junction 574 and through wire 572 through contacts 570 and 564 by way of movable contact 556 to the projection lamp 65. Thus, the shutter is retracted and the projection lamp is turned on to make an exposure. It will be realized that the push button 484 is released very shortly after it is depressed.

10 When the timer completes its cycle, the contacts 586 and 588 are reopened, whereby the shutter solenoid 350 is deenergized. The shutter is spring returned to its cut-off position and contacts 470 are reclosed. However, projection lamp 65 remains on.

15 With the contacts 470 reclosed, a circuit is completed from the aforementioned junction 574, through contacts 470 and limit switch 436 to motor 240 and through wire 20 604 back to the left side of the supply line. Also from junction 610 between contacts 470 and limit switch 436 a circuit is established through wire 612, through contacts 506 and 504 with shorting bar 502, and back through wire 606 to the clutch solenoid 242 and thence to the 25 left side of the supply line. Accordingly, the motor is effective to drive the paper feed rolls or rollers 258 and 266.

20 Also concurrently therewith, from the aforementioned junction 610 a circuit leads through wire 608 to wire 596 and thence to photoelectric cell 460. With no light on this cell it has a very high resistance, and may be considered an open circuit from the other side of the photocell where 598 leads to relay 600 which is returned through wire 602 to the left side of supply line 478.

25 Roller 258 frictionally drives roller 378 which turns its gear 396. This acts through gears 416 and 418 to drive segment 420, and thus to lift the photocell assembly. The distance through which the photocell assembly is lifted is directly proportional to the movement of the feed rolls, and when the photocell window 464 is raised to intercept the light bar 132 projected from the slide, the resistance of photocell 460 suddenly goes to zero, whereupon relay 600 is energized to open contacts 528 and 530. This causes relay 512 to drop out, whereupon contacts 516 and 518 separate, and whereupon contact 520 moves back from contact 524 to 522, thus breaking the circuit to the motor 240 and to the clutch solenoid 242, whereupon the brake portion of the clutch suddenly stops the driving shaft to halt advance of the paper.

30 As will be understood, the distance through which the photocell assembly must rise before the window encounters the light projected through the light bar 132 is dependent upon the height of the light bar. Thus, regardless of the width of the character as explained in connection with FIGS. 6, 6a and 6b, there will be a uniform spacing between characters or letters.

35 The uniform spacing between characters is adjustably predeterminable by means of the knob 412 and threaded shaft 410. This adjustably predetermines the rest position of the photocell assembly, and hence the distance through which the photocell assembly must rise to encounter the light beam. Thus, the setting can be predetermined to provide close spacing or large spacing. Once the spacing has been determined, the space between successive letters or characters will be constant. If the printed size of the character is increased or decreased, the spacing will be increased or decreased proportionately, unless the rest position of the photocell assembly is again adjusted.

40 The position of the projected light beam relative to the printing area will vary somewhat right or left, looking in the direction of the projected beam, in accordance with the degree of enlargement or reduction in size of the projected image, although the length of the bar com-

penses for this in large measure. This is further compensated for by adjusting the slide 450 carrying the photo-cell assembly back and forth. The position can be determined experimentally, but preferably is read from the scale 458 in accordance with the master chart or slide rule used in setting up the position of the projection unit and the focus.

A typical printed line is shown in FIG. 19. The paper strip feeds downwards, as will be appreciated, and the position of each light bar 132 relative to the corresponding character 128 is readily seen. It will be appreciated that the characters, although shown in black, do not appear black until the strip of photosensitized paper has been developed. The spacing of the light bars 132 will be seen to be quite non-uniform, yet the relation of each bar to its corresponding letter or character is constant. It is to be realized that each letter or character starts at the same height down on the slide, and hence is a uniform distance up on the paper strip from the cutoff point as determined by the light bar.

Reference should be made to FIG. 3a for the showing of a minor modification of the invention to speed up operations. In place of the push button switch 484 on the control unit, there is provided a low travel switch 614 having a push button 484a thereon engageable by the handle or finger piece 64. This speeds up operation somewhat, since the switch is operated as soon as the slide is fully inserted, and need not wait for shifting of the hand to the switch button 484. The internal construction of the switch 614 is identical with that discussed in connection with the push button 484 in the electric wiring diagram of FIG. 20. The switch can of course be located elsewhere for automatic operation upon insertion of the slide changing element, or it could be arranged for operation by the foot instead of the finger, as will be readily understood.

Although reference has been made throughout to "strip" printing and to printing on a "strip" of paper, it will be apparent that the principles and most of the mechanics of the invention are equally applicable to photosensitized material of greater width or thickness than might be normally be called a "strip." Furthermore, it will be apparent that transparent photographic film could be used instead of paper for printing, and that either could be processed for white-on-black images instead of the black-on-white shown.

The specific embodiments of the invention as herein shown and described are by way of illustration. Changes in structure will no doubt occur to those skilled in the art and will be understood as forming a part of the present invention insofar as they fall within the spirit and scope of the appended claims.

The invention is claimed as follows:

1. An optical printing machine comprising: means for providing a type font adapted to selected optical projection of the characters thereof, said type font having a plurality of index marks respectively associated with the characters thereof and positioned in accordance with the size of the respective characters; optical projection means for selectively optically selecting a character of said type font; a printing station; means providing a supply of photosensitive printing material in strip form; feeding means for intermittently advancing said strip of photosensitive printing material relative to said printing station and including a pair of opposed strip feed roller means bearing on said strip on opposite sides thereof; and control means connected to said optical projection means and to said feeding means, said control means comprising photosensitive means initially positioned away from the projection path of the index mark corresponding to the character being projected and movable into position to intersect the projected index mark, said photosensitive means being activated by said projected index mark to actuate said control means and limit movement of said photosensitive printing material relative to said printing

station, said control means further including moving means driven in synchronism with said roller means, said moving means including a driven roller, means mounting said driven roller for movement transverse of its axis into and out of driving engagement with said strip feed roller means, means normally holding said driven roller in driving engagement with said strip feed roller means to move said photosensitive means from an initial position to the position intersecting the projected index mark, and means for disabling said moving means for return of said photosensitive means to an initial position, said disabling means comprising means for retracting said driven roller from driving engagement with said strip feed roller means.

5 2. A printing machine as set forth in claim 1, wherein the retracting means comprises a movable member fixed relative to the driven roller axis, a fixed member adjacent said movable member, and a cam member movable into position between said movable and fixed members to force said movable and fixed members apart and hereby to retract said driven roller.

10 3. A printing machine as set forth in claim 2 and further including a shutter disposed adjacent to said printing station, a pivoted shaft mounting said shutter for movement in front of and away from said printing station, said cam member being mounted on said pivoted shaft.

15 4. An optical printing machine comprising: a base means; a storage means supported by said base means for holding photosensitive printing material; a printing station supported by said base means; drive means supported by said base means for moving the photosensitive printing material relative to said printing station; roller means supported by said base means, said roller means being movable from a first roller position in engagement with said drive means to a second roller position disengaged from said drive means; photoelectric means connected to said roller means for sensing when said printing material has been moved a predetermined distance relative to the printing station, said photoelectric means being moved from a first position to a second position adjacent to said printing station by said drive means when said roller means is in the first roller position, said photoelectric means being movable from the second position to the first position when said roller means is in the second roller position; a projector assembly mounted on said base means, said projector assembly including a light source and an optical lens means for projecting an image; slide tray means supported by said base means and associated with said projector assembly, said slide tray means including a generally cylindrical body means having a plurality of radially extending filing locations; a plurality of slide members positioned in the filing locations in said slide tray means, said slide members having a type character and an index mark associated with the type character; slide positioning means supported by said base means to move a selected slide member from a filing location in said slide tray means to a position intermediate said light source and said optical lens means to project an image of a selected type character and associated index mark; shutter means mounted on said base means, said shutter means being movable from a first shutter position intermediate the printing station and said optical lens means to a second shutter position, said shutter means in said first shutter position blocking the projection of an image of a type character onto said photosensitive printing material, and said shutter means in said second shutter position being spaced apart from said printing station to enable an image of a type character to be projected onto said photosensitive printing material at said printing station; actuator means connected to said roller means and to said shutter means, said actuator means being operable to move said shutter means from said first shutter position to said second shutter position, and said actuator means being operable to move said roller means from said first roller position to said second roller position; circuit means

connected to said light source, said drive means and to said actuator means, said circuit means including position sensing means associated with said shutter means to disable said drive means from moving said photosensitive printing material relative to said printing station when said shutter means is in said second position; control switch means connected to said circuit means, said control switch means being selectively actuatable to contemporaneously energize said light source, and to operate said actuator means to move said shutter means to said second shutter position and to move said photoelectric means to said first position by moving said roller means to said second roller position for enabling an image of a type character to be projected onto the photosensitive printing material at said printing station; and timer means connected to said circuit means, said timer means operating said actuator means at the end of a predetermined time period to move said shutter means from said second shutter position to said first shutter position and to move said roller means from said second roller position to said first roller position, said drive means being energized by actuation of said position sensing means by movement of said shutter means to said first position to move said photosensitive printing material relative to said printing station and to move said photoelectric means from said first position to said second position by rotating said roller means, the image of said index mark being projected on said photoelectric means in said second position to activate said photoelectric means to deenergize said drive means.

5. An optical printing machine comprising: a longitudinally extending base member; a projector unit mounted on said base member, said projector unit including an optical lens assembly for projecting an image; indicia means supported by said base member adjacent to said projector unit, said indicia means including a font of type characters and an index mark associated with each type character of said font of type characters; indicia positioning means mounted on said projector unit for positioning a selected type character and the associated index mark in a position adjacent said optical lens assembly to enable said optical lens assembly to project an image of the selected type character and an index mark associated with the selected type character; a printing unit mounted on said base member in a spaced-apart relationship relative to said projector unit; photosensitive printing material mounted in a storage means on said printing unit; drive means mounted on said printing unit for moving said photosensitive printing material past a printing station, said drive means including first roller means mounted on a first side of said photosensitive printing material and a second roller means mounted on a second side of said photosensitive printing material, said first and second roller means being in frictional engagement with said photosensitive printing material; shutter means mounted on said printing unit; first actuator means connected to said shutter means to move said shutter means from a first shutter position intermediate the printing station and said optical lens assembly to a second shutter position, said shutter means in said first shutter position blocking the projection of an image of a type character onto said photosensitive printing material, and said shutter means in said second shutter position being spaced apart from said printing station to enable an image of a type character to be projected onto said photosensitive printing material at the printing station; control circuit means connected to said first actuator means and to said drive means, said control circuit means including adjustable timer means connected to said first actuator means to retain said shutter means in the second shutter position to enable an image of a type character to be projected onto said photosensitive printing material at the printing station for a predetermined time period to form an image of the type character on the photosensitive printing material, said timer means operating said first actuator means to move said shutter means from the second shutter position to the first shutter position after the predetermined time period to be spaced a predetermined distance apart.

5. A period has elapsed; photoelectric means mounted on said printing unit for sensing when said printing material has been moved for a predetermined distance relative to the printing station; third roller means mounted in engagement with said second roller means to move said photoelectric means from a first position to a second position as said first and second roller means are rotated to move said photosensitive printing material relative to the printing station; and control circuit means connected to said photoelectric means and said drive means, said control circuit means including second actuator means associated with said third roller means to disengage said third roller means from said second roller means to enable said photoelectric means to return to the first position.

15. An optical printing machine comprising: a longitudinally extending base member; a projector unit mounted on said base member, said projector unit including an optical lens assembly for projecting an image; a font of type characters associated with said projector unit; an index mark associated with each character of said font of type characters; positioning means supported by said base member for moving a selected type character to a position adjacent said optical lens assembly to enable said optical lens assembly to project an image of the selected type character and the associated index mark; a printing unit mounted on said base member in a spaced apart relationship relative to said projector unit; storage means mounted on said base means for holding photosensitive printing material; drive means mounted on said printing unit for moving the photosensitive printing material past a printing station; shutter means supported by said base means adjacent to said printing unit; actuator means connected to said shutter means to move said shutter means from a first shutter position intermediate the printing station and said optical lens assembly to a second shutter position, said shutter means in said first shutter position blocking the projection of an image of a type character onto the photosensitive printing material, and said shutter means in said second shutter position being spaced apart from said printing station to enable an image of a type character to be projected onto said photosensitive printing material at the printing station; control circuit means connected to said actuator means and to said drive means, said control circuit means including position sensing means associated with said shutter means to disable said drive means from moving said photosensitive printing material when said shutter means is in the second shutter position, said control circuit means further including adjustable timer means connected to said actuator means for the shutter means to retain said shutter means in the second shutter position to enable an image of a type character to be projected onto said photosensitive printing material for a predetermined time period to form an image of the type character on the photosensitive printing material; said actuator means moving said shutter means from the second shutter position to the first shutter position after the predetermined time period has elapsed; photoelectric means mounted on said printing unit for sensing when the printing material has been moved for a predetermined distance relative to the printing station, said photoelectric means being moved relative to the printing station by said drive means when said shutter means is in the first shutter position after the predetermined time period has elapsed, said drive means moving said photoelectric means from a first position to a second position wherein an image of an index mark associated with a type character is projected onto said photoelectric means, said drive means moving said photosensitive printing material relative to said printing station as said photoelectric means is moved from the first position to the second position; and adjusting means mounted on said printing unit to selectively vary the distance from the first position of said photoelectric means relative to said printing station, said adjusting means enabling images of the type character formed on said photosensitive printing material to be spaced a predetermined distance apart.

7. An optical printing machine comprising: a base means; a printing assembly supported by said base means, said printing assembly including drive means to move photosensitive printing material past a printing station; a projector assembly supported by said base means, said projector assembly including a light source and an optical means for projecting an image onto the photosensitive printing material at the printing station; shutter means supported by said base means; actuator means connected to said shutter means, said actuator means being operative to move said shutter means from a first position intermediate the printing station and the optical means to a second position, said shutter means in said first position blocking the projection of an image onto said photosensitive printing material by said optical means and said shutter means in said second position permitting an image to be projected onto said photosensitive printing material by said optical means; slide tray means supported by said base means and associated with said projection assembly for holding a plurality of slide members; positioning means supported by said base means to move a selected slide member from a first position in said slide tray means to a second position intermediate said light source and said optical means; control switch means supported by said base means, said control switch means being actuated by said positioning means in moving a selected slide member from the first position in the slide tray to the second position intermediate the light source and optical means; circuit means interconnecting said control switch means, the light source, said actuator means and the drive means; said circuit means being energized by the actuation of said control switch means to energize the light source to project an image of indicia on the slide member, and to contemporaneously therewith operate said actuator means to move the shutter means to said second position to enable the image of the indicia on the slide member to be projected onto the photosensitive printing material at the printing station and to disable said drive means against moving the photosensitive printing material relative to the printing station; and timer means connected to said circuit means and said actuator means to enable said actuator means to move the shutter means from said second position to said first position at the end of a predetermined time period, said photosensitive printing material being exposed by the projection for the predetermined time period of the image of the indicia on the slide member to form similar indicia on the photosensitive printing material.

8. An optical printing machine as set forth in claim 7 further including: position responsive means mounted on said printing assembly and connected to the drive means; said position responsive means being actuated by said shutter means when said shutter means is in said first position to energize said drive means to move the photosensitive printing material for a predetermined distance relative to said printing station.

9. An optical printing machine as set forth in claim 7 wherein: said slide tray means includes a generally cylindrical rotatable body member having a plurality of radially extending filing locations for holding said slide members, said slide tray means being rotated relative to said projector assembly to locate a selected slide member for axial movement by said positioning means to a location intermediate said light source and said optical means.

10. An optical printing machine comprising: a base means; drive means supported by said base means for moving photosensitive printing material relative to a printing station, said drive means including a first roller means positioned in engagement with the photosensitive printing material; second roller means supported by said base means, said second roller means being movable from a driving position in frictional engagement with said first roller means to an idler position spaced apart from said first roller means; photoelectric means connected to said second roller means for sensing when the printing mate- 75

rial has been moved for a predetermined distance relative to the printing station; said photoelectric means being moved from a first position to a second position adjacent to said printing station by rotation of said first roller means when said second roller means is in the driving position, said photoelectric means being movable from the second position to the first position when said second roller means is in the idler position; actuator means connected to said second roller means to move said second roller means from the driving position to the idler position; a projector assembly mounted on said base means, said projector assembly including a light source and optical means for projecting an image onto the photosensitive printing material at said printing station; first and second indicia means supported by said base means and associated with said projector assembly; positioning means supported by said base means to move said first and second indicia means to a position intermediate said light source and said optical means; control switch means supported by said base means, said control switch means being actuated by said positioning means in moving the selected first and second indicia means to the position intermediate the light source and optical means; circuit means interconnecting said control switch means, the light source, said actuator means and the drive means; said circuit means being energized by actuation of said control switch means to energize the light source to project an image of the first indicia means onto the photosensitive printing material at said printing station and to project an image of the second indicia means onto said photoelectric means when said photoelectric means is in the second position and to operate said actuator means to move said second roller means to the idler position to enable said photoelectric means to move to said first position; and timer means connected to said actuator means and said drive means to operate said actuator means at the end of a predetermined time period to move said second roller means from the idler position to the driving position and to energize said drive means at the end of the predetermined time period to rotate said first roller means to move said photosensitive printing material relative to the printing station and to drive said second roller means, said photoelectric means being moved from the first position to the second position by said second roller means, said photoelectric means in said second position sensing the image of said second indicia means to disengage said drive means to stop the movement of said photosensitive material relative to the printing station.

11. An optical printing machine as set forth in claim 10 further including: adjustable stop means supported by said base means for selectively varying the relationship of the first position for said photoelectric means relative to the second position for said photoelectric means to vary the spacing of a series of images formed on said photosensitive printing material.

12. An optical printing machine comprising: a base member; a projector unit mounted on said base member, said projector unit including an optical lens assembly for projecting an image; a slide tray supported by said base member and associated with said projector means; a plurality of slide means positioned in said slide tray, said slide means including a type character and an index mark associated with said type character; slide positioning means mounted on said projector unit for moving a slide means from said slide tray to a position adjacent said optical lens assembly to project an image of a type character and an index mark associated with the type character; control switch means mounted on said projector means, said control switch means being actuated by said slide positioning means as a slide means is positioned adjacent said optical lens assembly; a printing unit mounted on said base member in a spaced-apart relationship relative to said projector unit; storage means mounted on said printing unit for holding photosensitive printing material; drive means mounted on said printing unit for mov-

ing the photosensitive printing material from said storage means and past a printing station; shutter means mounted on said printing unit; actuator means connected to said shutter means to move said shutter means from a first shutter position intermediate the printing station and said optical lens assembly to a second shutter position; said shutter means in the first shutter position blocking the projection of an image of a type character onto the photosensitive printing material, and said shutter means in said second shutter position being spaced apart from said printing station to enable an image of a type character to be projected onto the photosensitive printing material at the printing station; control circuit means connected to said control switch means, said actuator means and said drive means, said control circuit means being energized by actuation of said control switch means to operate said actuator means to move said shutter means from the first shutter position to the second shutter position, said control circuit means including position sensing means associated with said shutter means to disable said drive means from moving the photosensitive printing material when said shutter means is in the second shutter position, said control circuit means further including adjustable timer means connected to said actuator means for the shutter means to retain said shutter means in the second position to enable an image of a type character to be projected onto said photosensitive printing material at the printing station for a predetermined time period to form an image of the type character on the photosensitive printing material, said timer means operating said actuator means to move said shutter means from the second shutter position to the first shutter position after the predetermined time period has elapsed; photoelectric means mounted on said printing unit for sensing when the photosensitive printing material has been moved a predetermined distance relative to the printing station, said photoelectric means being moved relative to the printing station by said drive means when said shutter means is in the first shutter position

after the predetermined time period has elapsed, said drive means moving said photoelectric means from a first position to a second position wherein an image of an index mark associated with a type character is projected onto said photoelectric means, said drive means moving said photosensitive printing material relative to said printing station as said photoelectric means is moved from the first position of said photoelectric means to the second position of said photoelectric means; and adjusting means mounted on said printing unit to selectively vary the distance from the first position of said photoelectric means relative to said printing station, said adjusting means enabling images of type characters formed on said photosensitive printing material to be spaced a predetermined distance apart.

15 13. An optical printing machine as set forth in claim 12 further including: a cutter bar mounted intermediate said drive means and said printing station, said cutter bar being movable to cut an exposed portion of the printing material from a main supply of the printing material, whereby said drive means is in engagement with printing material extending from said main supply of printing material after said exposed portion of said printing material has been cut from said main supply of printing material.
